UNITED STATES PATENT OFFICE

JAMES MANGIN, OF NEW BRUNSWICK, NEW JERSEY, ASSIGNOR TO NEW BRUNSWICK ELECTRIC SUPPLY COMPANY, OF NEW BRUNSWICK, NEW JERSEY, A CORPORATION OF NEW JERSEY

ADJUSTABLE CROSSBAR OR STRAP FOR ELECTRIC FIXTURES

Application filed March 6, 1930. Serial No. 433,716.

The present invention relates to devices adapted for use as accessories in attaching electric fixtures in cooperative relation to outlet boxes to which the fixtures may be electrically connected and particularly refers to cross bars or straps adapted to be fastened to an outlet box for supporting an electric fixture.

The principal object of the invention is to provide a device of the class described which may be readily adjusted to support hanging fixtures having "bell" closures of various diameters.

Another object is to provide a device of the above-referred-to type comprising two relatively movable elements which, when combined, may be adapted for use with the round type of outlet box for supporting hanging fixtures from a ceiling and when used singly may be adapted for use with the rectangular type of outlet box for supporting wall fixtures.

A further object is to provide an adjustable cross bar or strap which is of relatively simple construction yet durable and may be easily manufactured in large quantities at relatively small cost by virtue of the fact that the elements of the strap are exactly alike and may be stamped or pressed out of single pieces of material with the use of a single die.

Other objects and advantages will appear more fully hereinafter from the following detailed description taken together with the accompanying drawings, in which

Fig. 1 is a plan view of the adjustable strap attached to a ceiling outlet box which is not provided with a fixture stud;

Fig. 2 is a sectional view thereof taken on line 2—2 of Fig. 1;

Fig. 3 is a side elevation of the strap;

Fig. 4 is a modification in which the yoke is provided with "struck-out" portions instead of the channels or guide fingers shown in Fig. 1;

Fig. 5 is a perspective view of one of the brackets used in attaching the strap to an outlet box which is not provided with a stud as in Fig. 1;

Fig. 6 is a partial sectional view showing the strap attached to a ceiling outlet box

which is provided with a stud and shows how a ceiling fixture is supported by the strap;

Fig. 7 shows a hanging fixture supported by the strap; and

Fig. 8 is an exploded perspective view showing one of the elements of the strap used singly for supporting a wall fixture from a wall outlet box.

Referring to the drawings and more particularly to Figs. 1 to 3 and 5 and 6, the strap of my invention comprises a pair of elements 10, each of which is provided with a yoke 11 and extensions 12. Each element is provided with an elongated aperture or slot 13 which extends between an aperture 14 and a relatively small elongated aperture 15 which are adapted to permit passage of fastening elements therethrough, such as screws or bolts, for attaching each of the elements to a wall outlet box when using it singly as indicated in Fig. 8, which will be explained more fully hereinafter. Adjacent each of the apertures 14 a threaded hole 16 is provided for receiving a screw by means of which the "bell" of an electric fixture may be attached to each of the elements, as shown in Figs. 6 and 7. Each yoke 11, is provided with a pair of channels or guide fingers 17 which are adapted to engage in slidable relation the corresponding extensions 12 of the elements. The slots 13 are arranged so that, when the elements are in slidable engagement with each other, the slots overlap to form an aperture 18 through which is adapted to pass a standard stud 19 which may be from one-eighth to three-eighths of an inch in diameter and the slot being of sufficient width to receive a stud of the largest diameter, as shown in Fig. 6. In Fig. 1, the outlet box 20 is not provided with the usual fixture stud and, therefore, the strap is attached to the box by means of the brackets 21 and the screws 22. Each bracket is provided with an aperture 23 of a diameter large enough to permit the head of the screws 22 to pass therethrough and terminating in a slot 24 which extends through half the length of the bracket and is of sufficient width to receive the stem of the screw. The bracket is further provided with a small portion 25 bent at right

angles to the main body portion of the bracket and adapted to bear against the edge of each of the elements 10 when placed in position, as shown in Fig. 1. The screws 22 are fastened to projections 26 of the outlet box 20.

From this description, it will be apparent that by sliding the extensions 12 through the yokes 11, the strap may be adjusted to any desired length to accommodate a fixture "bell" 10 of any diameter within certain limits which are determined by the lengths of the extensions which may be made of any dimensions suitable to practice for use with the different types of electric fixtures now on the market.

15 Referring to Figs. 6 and 7, the outlet box 20
is shown provided with a fixture stud 27.
When such a stud is provided, a strap is fas-
tened to the outlet box 20 by means of an aux-
iliary stud 19 which threads into the stud 27
20 and the strap is attached to the box by means
of the nut 28. The screws 22 and the brackets
21 are not required to support the strap, al-
though they may be used in combination with
the stud 19, if desired. The fixture "bell" 29
25 is attached in the same manner to the strap by
means of the screws 30. The bell 29 is shown
of the ceiling type, while in Fig. 7, the bell 29
is adapted to support a suspension fixture 31
by means of the usual chain 32.

30 In Fig. 4 is shown a modified embodiment of the strap in which the yokes 11 comprise "struck-out" portions 17' which form a slit instead of the guide fingers 17, shown in Fig. 1, and the extensions 12 are adapted to 35 slide through the slits so that the length of the strap may be varied. Each "struck-out" portion 17' is drilled to provide apertures 15' in place of the elongated apertures 15 shown in Fig. 1. The remaining details of construction are similar to those in the embodiment shown in Fig. 1.

In Fig. 8 is illustrated the application of one of the strap elements 10 for use by itself with a wall outlet box 33. The strap element 10 is adapted to be attached to the outlet box 33 by means of screws 34 which pass through the apertures 15 and 14 and are fastened to the projections 35 on the outlet box 33. The auxiliary stud 19 is secured to the element 10 by means of the nuts 36, one located on each side of the element 10. The auxiliary stud 19 may be positioned anywhere along the length of the stud so that it may be aligned with the aperture 19' on the fixture plate 37 of the fixture 38 which is shown as of the wall type. After the auxiliary stud 19 is secured to the element 10, the element is then fastened to the outlet box and the fixture plate 37 placed against the outlet box with the stud 19 projecting through the aperture 19' to receive the fixture nut 39.

It will be apparent that by the use of my improved fixture strap, the number of accessory elements required will be reduced in 65 that my strap elements are exactly alike and,

when used in combination, form an adjustable strap for supporting ceiling fixtures and, when used singly, provide a wall box strap for supporting wall fixtures. Because of the simplicity of construction, the strap elements may be easily manufactured and sold at a much lower cost than the straps now generally used and the elements may be sold singly.

While I have shown only two modifications of my invention for the purposes of illustration and description, it will be apparent to those skilled in the art that other modifications and changes may be made therein without departing from the scope of the invention and I, therefore, desire to be limited only by the scope of the appended claims.

I claim:

1. An adjustable fixture strap comprising two similar elements, each provided with a yoke and an extension, each of said yokes comprising a struck-out raised strap-like portion forming a slit with the yoke body through which the extension of the other element is adapted to slidably extend, each of said elements having apertures adapted to receive fastening elements for attaching said strap to an outlet box and for attaching a fixture to said strap.

2. An adjustable fixture strap comprising two similar elements, each provided with a yoke and an extension, each of said yokes comprising a struck-out raised strap-like portion forming a slit with the yoke body through which the extension of the other element is adapted to slidably extend, each of said elements having an aperture adapted to receive fastening elements for attaching a fixture to said strap and an elongated aperture, said last-mentioned apertures being adapted to overlap to permit passage through said elements of fastening elements for attaching said strap to an outlet box. 100 105
